UNITED STATES PATENT OFFICE.

GIUSEPPE F. PINSUTI, OF NEW YORK, N. Y.

BOTTLE-NECK-CONNECTING BAND.

1,162,877.

Specification of Letters Patent.

Patented Dec. 7, 1915.

Application filed August 17, 1914. Serial No. 357,165.

To all whom it may concern:

Be it known that I, GIUSEPPE F. PINSUTI, a citizen of the United States, residing at New York, in the county of New York and State of New York, have invented certain new and useful Improvements in Bottle-Neck-Connecting Bands; and I do declare the following to be a full, clear, and exact description of the invention, such as will 5 enable others skilled in the art to which it appertains to make and use the same.

This invention relates to improvements in bands for permanently connecting sectional bottle necks.

15 The object of the invention is to provide a device of this character so constructed as to avoid all possibility of separation of the sections without first breaking the band or one of the sections, and to prevent turning of the sections relatively to 20 each other which would permit the unauthorized refilling of the bottle.

With the above and other objects in view, the invention consists of certain novel features of construction, combination and arrangement of parts as will be more fully described and claimed.

In the accompanying drawings: Figure 1 represents a front elevation of a portion of 30 a bottle neck equipped with this improved band; Fig. 2 is a vertical section thereof; Fig. 3 is a similar view taken on a plane at right angles to Fig. 2; Fig. 4 is a transverse section taken on the line 4—4 of Fig. 35 1; Fig. 5 represents a transverse section taken on line 5—5 of Fig. 2.

In the embodiment illustrated, a bottle neck 1 is shown having its upper end 2 formed separately and connected by the 40 band 3 which constitutes this invention. The section 2 of this bottle neck is shown reduced at its outer end forming a shoulder 4 on its outer face and also a shoulder 5 on its inner face.

45 The sections 1 and 2 of the bottle neck are provided on their outer faces preferably at diametrically opposite points, with recesses 6 and 7 which are disposed in longitudinal alinement to receive cooperating 50 locking ribs 8 formed on the band 3, preferably by indenting the side walls of said band as is shown clearly in Figs. 3 and 4.

As shown, the band 3 is provided with an annular rib 9 adapted to fit a corresponding 55 groove 10 on the bottle neck section 1 and the inner end of said band is turned in-

wardly around a shoulder 11 formed on said bottle neck section whereby the band is held on said section against longitudinal movement. The upper or outer end of the 60 band is crimped over the shoulder 4 of the section 2 as shown at 12 and is provided beyond said crimped portion with a vertical flange 13 which snugly fits the reduced portion of the section 2 and thus firmly 65 locks the two sections together against longitudinal separation.

When the band on collar 3 has been applied to the two sections 1 and 2 with the inwardly extending ribs 8 engaged with the alined recesses 6 and 7, of the bottle neck sections, it will be obvious that the band cannot be turned on the sections nor the sections turned relatively to each other as these interlocking members will hold them 70 firmly against said movement and thus all danger of the bottle being filled in this manner is avoided. It is also obvious that the circumferential rib 9 when engaged with the corresponding annular groove 10 in the 75 bottle neck section, will, in connection with the shouldered portion 4 of the section 2 and the reduced outer end of the band, hold the sections against longitudinal separation as above set forth.

I claim as my invention:

1. A band for connecting sectional bottle necks provided with corrugations for engaging a top neck section, a flange arranged beyond said corrugations forming a collar of smaller diameter than the diameter of the body portion of the band, said corrugations being formed between said body portion and flange, and means for connecting said band with a bottle neck.

2. The combination with a bottle neck section having a plurality of longitudinally extending corrugations, of a band for connecting said section with a bottle neck, said band having a reduced end with a plurality of longitudinally extending corrugations formed between it and the body of the band for interlockingly engaging the corrugations of said section, and means for connecting said band with a bottle neck.

3. The combination with a bottle neck section having a plurality of longitudinally extending corrugations, of a band for connecting said section with a bottle neck and having a plurality of longitudinally extending corrugations for interlockingly engaging the corrugations of said section, said

band having a straight flange extending longitudinally beyond said corrugations, and of less diameter than the body of the band, the corrugations being formed between said flange and body, and means for connecting said band with a bottle neck.

4. The combination with a bottle neck section having a plurality of longitudinally extending corrugations, of a band having one end contracted and provided with a plurality of longitudinally extending corrugations at the base of said contracted portion between it and the body of the band, a longitudinally extending flange arranged on the said contracted portion forming a collar of smaller diameter than the diameter of the body portion of the band, and means for connecting said band with a bottle neck.

5. The combination with a bottle neck composed of two transversely separable sections having recesses in their outer faces disposed for alinement when the sections are

in a predetermined position, of a band for connecting said sections having a rib on its inner face positioned to engage the alined recesses in the two sections. 25

6. The combination with a bottle neck composed of two transversely separable sections each provided in its outer face adjacent the inner edge thereof with a recess, the recesses in one section being adapted to aline with those in the other, annular beads formed on the outer faces of said neck sections, of a connecting band having means for engaging said beads to hold said sections against separation, and means for engaging the alined recesses in said sections. 30 35

In testimony whereof I have hereunto set my hand in presence of two subscribing witnesses.

GIUSEPPE F. PINSUTI.
